BLOCK FLOOR SECTION

Bailey Peyton Brien, Chattanooga, Tenn.

Application January 21, 1936, Serial No. 60,087

6 Claims. (Cl. 20—75)

My invention relates to block floors and more particularly to improvements in block floor sections, and for maintaining such floors in their assembled relation.

It has been the practice in the prior art to assemble several blocks together by a spline or strip into a small section, then assemble such sections into a floor by tongue and groove connections. Such a structure is disclosed in the patent to Parsons, 1,454,250. This construction relies entirely upon the spline or strip for securing the blocks in assembled relation. As there is a tendency for the spline or strip to become loose in its seat there is a great danger of spreading of such blocks longitudinally of the section. In addition the blocks are free to warp and spread transversely, thus creating a broken or uneven line along the sections producing cracks in the floor, and causing great difficulty in laying it.

Other instances in the prior art where problems of this character arise are in the cases where block flooring formed by a plurality of blocks are built up from pieces. In order to give a proper design this flooring is laid so that the longitudinal axis of corresponding pieces in adjacent blocks are at right angles to each other. Inasmuch as such pieces tend to warp and spread more transversely than longitudinally, some blocks will extend beyond the section line to give an uneven or broken line and render it difficult to lay the floor, there being no means to limit the displacement of parts of one block in the section with respect to parts of others.

Splines or strips have been employed to hold built up strip flooring together and to secure pieces of individual blocks in assembled relation. The patent to Woloshin, 1,054,070 shows a built up floor employing strips or splines to secure the parts in assembled relation, while the patents to Goehst 662,376 and Larkins, 1,801,093, disclose splines for holding the individual blocks in assembled relation. However, these patents only disclose the use of splines or strips where they do not give rise to the problems of individual block flooring, except where these blocks in the later cited patents are laid as a part of a floor. This of course raises the problems for there is nothing tending to keep the blocks in line and in addition all of the problems of the Parsons patent, supra, are injected in a more marked degree.

A recognition of some of these problems has existed in bar flooring where an attempt was made by Mrokowski in Patent Number 966,347, to secure sections of bar flooring together by wires for preventing their relative displacement after

laying. Such an arrangement is not satisfactory, however, for the wires are easily loosened from the bars and permit spreading. Furthermore there is no feasible way of disposing the bars within the bars, and finally such sections cannot be altered by saw because of inevitable injury.

With a knowledge of the defects in and objections to the prior art, I have, as an object of my invention the provision of a block floor made in laid sections and reinforced by splines or strips extending throughout the length of such sections and seated in dove tail recesses in the aligned blocks of such sections.

Another object of my invention is to provide a block flooring laid in sections, each section comprising a plurality of blocks built up from pieces, said blocks being so related that the longitudinal axis of corresponding pieces in adjacent blocks are at right angles to each other, and splines or strips seated in grooves in said blocks for preventing their relative displacement.

A further object of my invention is to provide a section of block flooring comprising a plurality of blocks built up from pieces, said pieces and blocks being joined together by dove tail tongues and grooves, and splines or strips seated in dove tail slots in said blocks and extending the full length of the section to prevent relative displacement of said blocks and pieces due to the effect of weather and usage.

A still further object of my invention is to provide a section of block flooring comprising a plurality of blocks built up from pieces and all joined together by dove tail tongues and grooves, and splines or strips for maintaining the blocks in assembled position. Plain tongue and groove means is provided around the entire outer edge of the section for quick and easy assembly with others of the same character to form a floor.

Other objects and advantages of my invention will appear in the following specification, and the novel features will be particularly pointed out in the annexed claims.

Figure 1 shows a plan view of two blocks of a section. Figure 2 shows an end view of a block comprised in the section. Figure 3 shows a side view of two blocks of a section. Figure 4 shows an end view of a section (cross-section) of a block with the pieces thereof in unassembled relation. Figure 5 shows a floor made up of blocks laid in sections.

In the drawing numerals 1 to 6, inclusive, designate a section of block flooring embodying the preferred form of my invention. 7 and 8 designate splines or strips seated in dove tail

grooves in the bottom surface of such blocks and extending the full length of each section. Numerals 9, 10, and 11 designate pieces of an individual block whose longitudinal axes run parallel with the longitudinal axis of the section while numerals 12, 13, and 14 designate pieces of an individual block whose axes are perpendicular to the axis of the section. 16 designates a plain groove formed in one side of each block of the section to receive a plain tongue on the adjacent section, and 17 indicates a plain tongue running along the full length of the other side of the section for a similar purpose. 18, 19, 21, 22 designate dove tail tongues on the pieces for seating in corresponding grooves in adjacent pieces whereby the individual blocks are maintained in assembled relation. 20 designates a dove tail tongue for cooperation with a mating groove in an adjacent block whereby the blocks of the section are secured together.

The floor is assembled in the following manner:

The individual blocks are made by assembling the pieces so that the dove tail tongue on one piece is seated in the dove tail groove of the mating piece. As shown each block comprises three pieces, but this invention is not to be construed as limited to three pieces for it is recognized that any number may be used. Then the individual blocks are assembled to form a section many 30 blocks long but preferably only a single block wide, however, the invention is not limited to such. In the assembled section odd blocks have the longitudinal axis of the pieces in parallel relation and at right angles to the longitudinal axes 35 of the pieces of the even blocks. This results in a floor of unique design with no two adjacent blocks set in the same relation. The blocks of the section are secured together by interlocking dove tail tongue and groove connections.

When a plurality of blocks are assembled in this manner and are properly aligned to form a section the bottom surface of which contains one or more dove tail grooves extending the full length of the section and crossing each block. Splines 45 or strips 7 and 8 are disposed within these grooves. The effect of these splines or strips will be apparent upon reference to Figures 1 and 5.

If the splines or strips were not present blocks 1, 3 and 5 of the section would tend to warp, expand or be displaced due to the action of temperature and weather upon them. They would spread more along the transverse axes of the pieces than the blocks 2, 4, and 6 would expand along the longitudinal axes of their pieces. This 55 would result in a section formed of broken lines and would render it impossible to lay a smooth and even floor. The action of splines or strips 7 and 8 is to prevent relative movement or spreading between the blocks of the section, and results in a section presenting a straight line its entire length. This makes it possible to build up and finish the sections at the plant, send them to the place of installation where they may be easily and quickly and perfectly installed by assembling with like sections to give a perfect floor, and eliminate finishing after it has been laid with all the resulting dirt and inconvenience.

In the absence of sections formed in this manner, the floor must be formed by building up the 70 individual blocks, such a floor cannot be laid on a rough subfloor for the blocks will lie unevenly, and even though the subfloor be smooth, relative movement between the blocks while being assembled or after assembly results in an imperfectly fitted and ill constructed floor. Often

great cracks are apparent in the floor or sections are out of line spoiling the whole effect and advantages of block flooring. The use of splines or strips in the manner indicated permits the flooring to be laid on rough subflooring in much 5 the same manner as strip flooring. Such construction also maintains the desired symmetry and overcomes the tendency of cracks to form in the floor after laying.

After the section has been assembled it is to 10 be noted that its entire outer edge or circumference is formed with a plain tongue and groove. This permits the assembly of one section at a time by quickly correlating the plain tongue and grooves of mating sections. In this manner 15 whole sections are made at the plant where great precision can be obtained. Strips made in this manner may be easily cut to any desired length or shape by the ordinary hand saw, and such operation will in no way effect or injure the remaining part of the section.

It is seen that the spline or strip does not act to hold the blocks together, for this is accomplished by the dove tail tongues and grooves of the blocks and their pieces, but their functions 25 are to maintain the blocks in position and prevent relative movement.

It is also seen that block flooring may be laid on screeds or joice when assembled in sections with splines or strips just as in the case of strip 30 flooring. This greatly increases the utility of such flooring.

Having thus described my invention, I claim:

1. A block floor including a section, said section comprising a plurality of aligned blocks, means 35 for securing said section to another section, additional means for securing the blocks of said section together, and means extending substantially the full length of said section whereby to prevent relative displacement between said blocks. 40

2. In a preformed floor section comprising, a plurality of aligned blocks in end to end relation forming a section, each of said blocks including a plurality of pieces, tongue and groove means for securing said pieces together, tongue and groove 45 means for securing said blocks together, and strip means seated in said blocks and extending substantially the length of said section whereby to prevent relative movement between said blocks.

3. A preformed floor section comprising, a plurality of aligned blocks forming a section, each of said blocks including a plurality of pieces, the longitudinal axes of the pieces in the odd blocks being parallel and at right angles to the longitudinal axes of the pieces in the even blocks, dove tail tongue and groove means for securing the blocks together, and a plurality of strips seated in said blocks and extending substantially the length of the section whereby to maintain the blocks in assembled position at all times. 60

4. A preformed floor section comprising, a plurality of aligned blocks forming a section of one block width, dove tail tongue and groove means for securing said blocks together, spline means seated in said blocks and extending substantially the full length of said section for preventing relative displacement of said blocks, and tongue and groove means on said section whereby to facilitate quick assembly with similar sections. 65

5. A preformed floor section comprising, a plurality of aligned blocks forming a section, each of said blocks including a plurality of pieces, the longitudinal axes of the pieces in the odd blocks being substantially parallel and at an angle to the longitudinal axes of the pieces in the even blocks, 70

dove tail tongue and groove means for securing the blocks together, dove tail grooves in the bottom surface of each of said blocks extending substantially the full length of the section, and strips seated in said grooves for preventing spreading and other displacement of any of said blocks.

5. A block of the character described, comprising a plurality of pieces in side by side relation,

dove tail tongue and groove means on the adjacent edges of the cooperating pieces for securing them together against separation, a tongue on the free side of one outer piece and a corresponding groove in the free side of the other outer piece, whereby to facilitate assembling with other like blocks.

BAILEY PEYTON BRIEN.
